UNITED STATES PATENT OFFICE.

THOMAS H. ORR, OF OKMULGEE, OKLAHOMA.

BABBITTING MACHINE.

Application filed May 15, 1926. Serial No. 109,379.

This invention relates to a method of and machine for babbetting a connecting rod and main bearing or the like.

The object of the invention is to provide a method and machine of this character which is especially although not necessarily designed for use in rebabbetting the connecting rod and main bearings of automobiles and which greatly facilitates the babbetting operation and carries out the babbetting operation in such manner that the new Babbitt bearing provided is clear of all dross and burnt alloys in the babbitt and which eliminates pits and flaws in the new Babbitt bearings provided.

A further object is to provide a method and machine of this character which is of simple and durable construction, reliable and effective in operation, easy to control and comparatively simple and inexpensive to manufacture.

Other objects and advantages reside in certain novel features of the construction, arrangement and combination of parts which will be hereinafter more fully described and particularly pointed out in the appended claims, reference being had to the accompanying drawings, forming a part of this specification, and in which:—

Figure 1 is a perspective view showing a machine embodying the present invention.

Figure 2 is a view thereof in front elevation.

Figure 3 is a plan view of the machine, parts being broken away for the sake of illustration.

Figure 4 is a view in longitudinal vertical section on the line 4—4 of Figure 3, parts being shown in section for the sake of illustration.

Figure 5 is a sectional view on the line 5—5 of Figure 3, parts being shown in elevation for the sake of illustration.

Figure 6 is a sectional view on the line 6—6 of Figure 5.

Figure 7 is a group view in perspective of the parts shown in Figure 6.

Figure 8 is a detail view of one of the forks engageable with the clamp heads.

Figure 9 is a plan view of the funnel.

Figure 10 is a sectional view thereof, and

Figure 11 is a view illustrating the use of the device in rebabbetting one of the main bearings.

Referring to the drawings it will be seen that the machine comprises a suitable

frame, designated generally at 1, the frame 1 having a base plate 2 and an upstanding side plate 3, the plates 2 and 3 being suitably notched and cut away as may be necessary to accommodate the various operating parts of the machine. Bearing posts 4 and 5 are provided and have reduced extensions 6 at their lower ends, the extensions 6 extending through holes in the base plate 2 of the frame and being threaded to co-act with nuts 7 whereby the posts are secured to the frame. Lock washers 8 may be interposed between the nut 7 and the plate 2 to lock the posts 4 and 5 in position. A centering screw 10 is threadedly engaged with the post 4 and has a smooth and pointed or tapered centering end 11 at its inner end and a handle member 12 at its outer end. A similar centering pin, designated generally at 13, is rotatably mounted on the post 5, the centering screw 13 having a hand lever 14 fixed thereto and having its inner smooth and tapered end 15 transversely slotted to receive a key 16 which is fitted in a key-way 17 provided in one end of the mandrel, designated generally at 18. In this way the screw 13 is so connected to the mandrel that whenever the lever 14 is turned to turn the screw the mandrel 18 will also be turned. As the key 16 floats in the slot of the screw 13 it does not interfere with the centering action of the screw 13. The key 16 is tapered and the portion of the slot 17 which it engages is correspondingly tapered to prevent accidental displacement of the key. Of course, the smooth pointed end 11 of the screw 11 engages a correspondingly formed centering recess 19 provided in the end of the mandrel opposite the end engaged by the screw 13. With this arrangement the mandrel 18 may be readily taken from the screws by turning the screw 12 to disengage it entirely from the adjacent end of the mandrel. This will permit the mandrel to move axially to disengage it from the screw 13 to such an extent as to permit its transverse movement with respect to the screw 13 to entirely dismount the mandrel from the screws. When the mandrel 18 is moved transversely the extreme outer portion of the pointed end of the screw 13 passes through the slot 17. By a reverse operation the mandrel may be replaced on the screws.

As clearly shown in the drawings the mandrel has end sections 20 of cylindrical form having smooth peripheries. Between the end sections the mandrel is of reduced diam-

eter as indicated at 21 and is partially cut-away, as at 22. The mandrel is cut-away as only half of a bearing is babbitted at a time and consequently only half of the 5 peripheral or angular extent of the mandrel is actually used to shape and form the babbitt. At the center of the central portion or section of the mandrel a transverse tapered opening 23 is provided and it is through 10 this central opening that the babbitt is poured, as will be hereinafter more fully described. A pair of sleeve-like clamping heads 25 are snugly fitted on the end sections 20 of the mandrel in such manner that they may be 15 slid back and forth thereon. Each clamping head 25 has a semi-circular extension 26, the extensions 26 of the clamping heads confronting each other in the assembly. The adjacent end portions of the extensions 26 are 20 provided with grooves 27 and in the center of each groove 27 an upstanding semi-circular rib 28 is provided. In each groove 27 a reversible clamping and closing element 29 is 25 provided and consists of a semi-circular and arcuate web 30 having a groove 31 to receive the rib 28 and having oppositely directed flanges 32. The clamping and closure elements 29 are held engaged with the ribs of their grooves by means of a combined closure 30 and holding plate, designated generally at 35, the plate 35 being fitted flush up against the flat face of the cut-away portion 22 of the mandrel and being secured in any one of a number of adjustable positions by means of 35 screws 36 threaded into the mandrel and extending through slots 37 in the plate 35.

Means is provided for shifting the clamping heads 25 back and forth on the sections 20 and for holding them in set position. This 40 means includes a rotatable shaft 40 having oppositely threaded end sections 41 and 42, the extremities of the sections 41 and 42 being smooth and rotatably mounted in bearing brackets 43 provided on the plate 3 of the frame. A handle 44 is provided for turning the shaft 40. Nuts 45 and 46 are threadedly engaged with the sections 41 and 42, respectively, of the shaft 40. The nuts 45 and 46 are pivotally connected to levers 47 which 45 have yokes 48 at the ends thereof opposite their pivotal connection to the nuts 45 and 46. The arms of the yokes 48 are pivotally connected, as at 49, to semi-circular or semi-annular collars 50, the collars 50 being operatively fitted in annular grooves 51 provided 55 in the sleeve-like heads 25. A post 52 is provided on the frame between the levers 47, the lower end of the post having a reduced extension 53 fastened to the base plate of the frame by a nut 54 and lock washer 35. The upper end of the post is slotted, as at 56, to provide spaced arms 57 and 58. A short shaft, designated generally at 59, is rotatably mounted in a bearing 60^a provided therefor 60 in the arm 58 by means of a bearing sleeve 60

carried on the shaft and in a bearing ring 61 which is a driving fit in an opening 62 provided in the arm 57. On the portion of the shaft 59 which is located between the arms 57 and 58 eccentrics 63 and 64 of opposite throw are fixed by means of a key 65 driven into a key-way 66 in a shaft and into mating key-ways 67 in the eccentric discs (see Fig. 7). This key 65 also serves to fix the bearing sleeve 60 to the shaft 59. Links 68 and 69 are provided and have openings 70 and 71 in which the eccentric discs 63 and 64 are operatively received. The ends of the links 68 and 69 opposite those mounted on the eccentric discs are pivotally connected, as at 72, to lugs 73 pivoted to the levers 47, as indicated at 73^a. On the portion of the shaft 59 that projects rearwardly beyond the arm 58 a lock lever or hand lever 75 is fixed. When the lock lever 75 is turned in one direction it 75 rotates the shaft 59 to cause the eccentric discs 63 and 64 to shift the eccentric links 68 and 69 in opposite directions and away from the axis of rotation of the shaft 59. This shifts the levers 47 away from each other and spreads or shifts the clamping heads 25 away from each other. When the handle lever 75 is moved in an opposite direction, the eccentrics operate to draw the levers 47 and consequently the clamping heads 25 80 together. The nuts 45 and 46 constitute adjustable fulcrums for the levers 47 since when the levers 47 are shifted by moving the lever 75 they move or fulcrum about their pivotal connection to these nuts 45 and 46. The nuts 45 and 46 when shifted along the shaft 40 change the position of the clamping heads since at such time the levers 47 swing about the pivotal connection of the lugs 73 with the levers 47. This is an especially desirable feature in adapting the device for use with different sizes of connecting rods as this enables the clamping heads to be positioned to be quickly shifted into and out of engagement with the connecting rod by means of the 85 lever 75.

In employing the machine to rebabbitt a connecting rod bearing the proper size of mandrel is selected for the connecting rods to be rebabbitted. It is to be understood that the mandrels with their clamping means are provided in sets to take the connecting rods of various cars. Usually only five sets are necessary to take all of the various sizes of connecting rods. When the proper mandrel 105 has been selected and placed in the machine it is positioned as shown in Fig. 1 and the connecting rod is then positioned thereon as 110 illustrated in Figure 1. By using a rule or scale the connecting rod is centered over the 115 opening 23 of the mandrel. The connecting rod is on the opposite side of the mandrel from the plate 35 and this plate is adjusted to close the space between the inner faces of 120 the connecting rod and the mandrel. The 125 connecting rod is then rotated until the 130

plate is secured in adjusted position by tightening up the screws 36. When the connecting rod has been properly centered, it is clamped in position by manipulating the levers 44 and 75 and when the connecting rod is clamped in position the side edges of its flanges are firmly engaged by the flanges 32 of the closure and clamping elements 29.

When the connecting rod is clamped in position a centering device, designated generally at 80, is brought into engagement with the same and secured in such position so that after the first connecting rod has been properly centered by use of the rule or scale the others may be centered by engagement with the centering device. As shown in the drawing the centering device comprises an angular finger 81 having a slotted portion 82 adjustably clamped by a screw 83 to the plate 35. The finger 81 also has a connecting rod engaging portion 82. The connecting rod engaging portion 82 presses against the outside of the bolt hole of the properly centered connecting rod.

After the connecting rod has been centered and clamped the lever 14 is grasped to turn the mandrel over to position the connecting rod as shown in Figure 2. A funnel, designated generally at 85, is then mounted in the opening 23 of the mandrel. As shown in Figs. 4 and 5 the plate 35 has an opening 35^a to permit of the funnel being inserted in the openings of the mandrel. The funnel 85 comprises a tapered tubular body 86 having a crescent-shaped opening 87 in its lower end. The edge of the crescent-shaped opening is sharpened to provide a cutter 88. The upper end of the funnel 85 is entirely open. Adjacent the upper end of the tubular body a handle 89 is connected thereto. The molten babbitt is poured in through the funnel and flows in through the center of the mandrel and centrally into the bearing, then passes to the ends of the bearing. Molten babbitt is poured into the funnel until the funnel is completely filled. This subjects the babbitt in the bearing to the pressure of a considerable head of babbitt and also has the advantage of affording a surface exteriorly of the bearing to which the dross and burnt alloys in the babbitt arise.

At this point it will be noted that the invention involves a novel method which consists in introducing the molten babbitt into the central part of the bearing and permitting the babbitt to flow to the ends thereof. This is the principal step in the method but an auxiliary step of considerable importance consists in the introduction of the babbitt into the bearing in the manner specified while the babbitt is under a considerable head and also while it has a surface exteriorly of the bearing at which the impurities may arise. The advantage of feeding the babbitt centrally into the bearing consists in the fact

that the ends of the babbitt cool and exert equal pulls upon the hot central portion which being still molten and subjected to the pressure of a head of babbitt is well adapted to withstand this pulling without pitting or cracking as would be the case were the babbitt fed into the ends of the bearing.

After the babbitt has cooled sufficiently the handle 89 is utilized to rotate the funnel which brings the edge 88 into action to cause it to cut off the babbitt in the funnel from the babbitt of the bearing. Then the levers 44 and 75 or either may be utilized to disengage the clamping heads from the connecting rod. After this if the connecting rod still adheres to the mandrel and it usually will, due to the adhesion of the new babbitt thereto, it is removed by means of an ejector which consists of a lever 90 pivoted, as at 91, on the arm 57 and having an ejecting finger 92 pivotally connected thereto, as at 93. The ejecting finger 93 is arranged to extend down through the opening 23 of the mandrel when the lever 90 is swung downwardly. The lever 90 is normally held in an upright inoperative position by means of a spring catch 94 provided at the upper end of a supporting rod 95.

The invention may also be used for rebabbing main bearings of cylinder blocks and for rebabbing line shaft boxes, lathes, shapers, planers, or the like. In fact the machine may be used for rebabbing any bearing that is made in halves. In Fig. 11 the machine is shown in use for rebabbing the main bearing of the cylinder block B. At such a time only the mandrel is employed, the mandrel being taken from the centering screws. Of course, in conjunction with the mandrel 18 the clamping sleeves 25 and the funnel 85 are employed. A somewhat larger plate than the plate 35 is used, the plate employed being designated at 100 and being fastened by bolts or cap screws to the engine block and to the mandrel. The babbitt is introduced through the funnel 85 as before and the lower open end of the funnel projects down through an opening provided therefor in the plate 100 and through an opening in the mandrel.

I claim:

1. The herein described method of rebabbing bearings which consists in introducing molten babbitt into the center of the bearing and permitting it to flow to the ends thereof and subjecting the babbitt so introduced to a considerable head of molten babbitt whereby the babbitt which flows to the ends of the bearing is adapted to exert equal pull upon the hot central portion and the head pressure of the molten babbitt adapted to withstand pulling without pitting or cracking.

2. The herein described method of rebabbing bearings which consists in intro-

ducing molten babbitt into the center of the bearing and permitting it to flow to the ends thereof and subjecting the babbitt so introduced to a considerable head of molten babbitt whereby the babbitt which flows to the ends of the bearing is adapted to exert equal pull upon the hot central portion and the head pressure of the molten babbitt adapted to withstanding pulling without pitting or cracking, said head of molten babbitt having a surface above and exteriorly of the bearing to which the dross and impurities in the babbitt may flow.

3. A machine for rebabbitting bearings comprising a mandrel having an opening adapted to be located substantially centrally of the bearing to be rebabbitted, means for closing the ends of the bearing, and means for supplying babbitt through the opening 20 of the mandrel to the bearing.

4. A machine for rebabbitting bearings comprising a mandrel having an opening adapted to be located substantially centrally of the bearing to be rebabbitted, means for closing the ends of the bearing, means for supplying babbitt through the opening of the mandrel to the bearing, and ejecting means for displacing the babbitt bearing from the mandrel, and comprising an ejecting lever having a finger adapted to operate through the opening of the mandrel.

5. Ejecting mechanism for use in displacing babbitted connecting rod bearings from the mandrels on which they are rebabbitted 35 and comprising a lever having a finger extendable through the opening in the mandrel.

6. Ejecting mechanism for use in displacing babbitted connecting rod bearings from the mandrels on which they are rebabbitted 40 and comprising a lever having a finger extendable through the opening in the mandrel, and means for normally holding the lever in inoperative position.

7. A machine for rebabbitting bearings comprising a mandrel having an opening adapted to be centrally disposed with the bearing to be rebabbitted, heads slidably mounted on the mandrel and having elements engageable with the ends of the bearing to be rebabbitted, and means for shifting the heads back and forth on the mandrel.

8. A machine for rebabbitting bearings comprising a mandrel having an opening adapted to be centrally disposed with the bearing to be rebabbitted, heads slidably mounted on the mandrel and having elements engageable with the ends of the bearing to be rebabbitted, means for shifting the heads back and forth on the mandrel and comprising a rotatable shaft having oppositely threaded portions, nuts engaged with the threaded portions, levers pivotally connected to the nuts and having operative connection with the heads, and means connected with the intermediate portions of the levers for

shifting the same about the nuts as fulcrums.

9. A machine for rebabbitting bearings comprising a mandrel having an opening adapted to be centrally disposed with the bearing to be rebabbitted, heads slidably mounted on the mandrel and having elements engageable with the ends of the bearing to be rebabbitted, means for shifting the heads back and forth on the mandrel and comprising a rotatable shaft having oppositely threaded portions, nuts engaged with the threaded portions, levers pivotally connected to the nuts and having operative connection with the heads, means connected with the intermediate portions of the levers for shifting the same about the nuts as fulcrums and including manually operable eccentrics and links operated by the eccentrics and pivotally connected to the levers.

10. A machine for rebabbitting bearings comprising a mandrel having a transversely extending opening adapted to be positioned centrally of the bearing to be rebabbitted.

11. A machine for rebabbitting bearings comprising a mandrel having a transversely extending opening adapted to be positioned substantially centrally of the bearing to be rebabbitted, heads slidably mounted on the mandrel and having reduced clamping extensions, combined clamping and closure elements mounted on said extensions, means for shifting the heads of the mandrel and holding them in adjusted position, a plate engageable with said reduced extensions, and means for releasably securing the plate in any one of a number of adjusted positions to the mandrel, the plate having an opening registering with the opening in the mandrel.

12. A machine for rebabbitting connecting rod bearings comprising a mandrel having a reduced central portion provided with a transversely extending opening designed to be positioned substantially centrally of the bearing, sleeve-like heads slidably fitted on the end portions of the mandrel and having semi-circular extensions provided at their confronting ends with grooves, the grooves having upstanding arcuate ribs therein, semi-circular clamping and closure elements fitted in the grooves and comprising webs having grooves receiving the ribs, the webs having oppositely directed flanges, a plate engageable with the semi-circular extensions and with the combined closure and clamping elements, means for securing the plate to the mandrel in any one of a plurality of adjusted positions, the plate having an opening registering with the opening of the mandrel, the plate co-acting with the combined closure and clamping elements to confine the babbitt in the bearing.

13. A machine for rebabbitting bearings comprising a mandrel having a transversely extending opening adapted to be positioned substantially centrally of the bearing to be

rebabbitted, heads slidably mounted on the mandrel and having reduced clamping extensions, combined clamping and closure elements mounted on said extensions, means for shifting the heads of the mandrel and holding them in adjusted position, a plate engageable with said reduced extensions, means for releasably securing the plate in any one of a number of adjusted positions to the mandrel, 10 the plate having an opening registering with the opening in the mandrel, and a centering device mounted on the plate.

14. A machine for rebabbitting bearings comprising a mandrel having a transversely extending opening adapted to be positioned substantially centrally of the bearing to be rebabbitted, heads slidably mounted on the mandrel and having reduced clamping extensions, combined clamping and closure elements mounted on said extensions, means for shifting the heads of the mandrel and holding them in adjusted position, a plate engageable with said reduced extensions, means for releasably securing the plate in any one of a number of adjusted positions to the mandrel, 25 the plate having an opening registering with the opening in the mandrel, and a centering device mounted on the plate and comprising an angular finger adjustably secured to the 30 plate.

15. A machine for rebabbitting bearings comprising a frame having a bearing post

secured thereto, centering screws mounted on the bearing posts, a mandrel having its ends adapted to be engaged with the screws for 35 rotatably mounting the mandrel on the frame, one of the screws having a driving connection with the mandrel and having a handle whereby it may be turned, the mandrel having a portion provided with a transversely extending opening designed to be positioned substantially centrally of the bearing to be rebabbitted, clamping heads slidably mounted on the mandrel and co-operable with the ends of the bearing to be rebabbitted, a plate engaged with the mandrel and with the bearing, means for securing the plate to the mandrel, and means for shifting the heads on the bearing and for holding them in adjusted 40 position. 45

16. A machine for rebabbitting bearings comprising a mandrel having a transversely extending opening through which the babbitt is to be introduced into the bearing, and means for closing the ends of the bearing. 50

17. A machine for rebabbitting bearings comprising a mandrel having a transversely extending opening through which the babbitt is to be introduced into the bearing, means for closing the ends of the bearing, and a plate 60 co-operable with said last mentioned means and with the mandrel to confine the babbitt in the bearing. 65

THOMAS H. ORR.
